CONTROLLER FOR TOWING WINCHES AND
OTHER MACHINES

Eivind U. Lassen, Whitefish Bay, Wis., and Almon A. Johnson, Forest Hills, N. Y.; said Lassen assignor to Cutler-Hammer, Inc., Milwaukee, Wis., a corporation of Delaware

Application August 28, 1946, Serial No. 693,496

5 Claims. (Cl. 318—6)

1

This invention relates to control for towing winches.

An object of the invention is to improve in respect of hawser reclaiming, the control disclosed in our Patent No. 2,372,963, granted April 11, 1945.

The control of the aforementioned patent is such that the hawser for automatic payout must overcome motor torque opposing payout plus the friction of the winch and associated gearing, and such that the automatic reclaiming cycle is dependent upon a substantial drop in hawser pull. In practice such drop in pull was found almost always to follow promptly automatic payout but occasional unusual conditions were found to result in an unduly protracted period where the drop was insufficient to initiate the reclaiming cycle, such initiation having been made dependent upon a slight motion of the motor in reclaiming direction. When such conditions occurred the stalled motor was maintained energized to hold against hawser pull, whereas when the automatic reclaiming means is effective the motor is disconnected from circuit and braked to hold against hawser pull, which is preferable, and an object of the present invention is to overcome this minor disadvantage of the control of the patent.

Another object is to accomplish the desired results without modification of the means disclosed in the aforementioned patent except for the mere addition of a simple and reliable relay to parallel the previously provided friction switch operatively associated with the motor.

Another object is to provide improved reclaiming means which may be advantageously employed in winch control other than the specific form disclosed in the aforementioned patent.

Other objects and advantages of the invention will hereinafter appear.

The accompanying drawing shows diagrammatically one embodiment of the invention, it being understood that the embodiment illustrated is susceptible of various modifications without departing from the scope of the appended claims.

The control selected for illustration is except for the aforementioned added relay and its connections physically the same as that disclosed in the aforementioned patent, and the drawing hereof bears the same reference characters as the drawing of the patent. The patent not only shows the control but also shows the mechanism to be controlled and contains a full description of both, wherefore reference is hereby made to such patent to avoid need herein of further illustration

2

or a more detailed description of the control covered by the appended claims.

Referring to the drawing hereof, the winch drive illustrated comprises a motor M having an armature A and a separately excited field winding F. The motor armature is supplied by a generator G having an armature A', a separately excited field winding F' and a series field winding F². The field windings F and F' are supplied from lines L' and L². The generator field winding F² acts cumulatively with the field winding F' under certain conditions, and differentially under other conditions. The motor has a brake (not illustrated) to be electromagnetically controlled by means including a winding B.

The loop for the motor and generator armatures includes resistors R' to R⁶ which are under the control of switches 1D to 5D, and also includes series coils 1FD' and 1FA' for control of relays 1FD and 1FA. Also the loop has connected across the same a winding VR' for a voltage relay.

In the foregoing respects the disclosure hereof is the same as that of the aforementioned patent, whereas the drawing hereof shows connected across the motor armature an added winding 1VR' for control of an additional relay 1VR which has normally engaged contacts 1VR². The contacts and winding of relay 1VR have been shown in a widely separated relation and hence their connection has been indicated by a broken line extending from said contacts to the plunger of said winding.

Except for the added voltage relay just mentioned the control means shown are the same as those found in the aforementioned patent, and will be understandable from the following description of operation which as to common subject matter is mere repetition of the description found in the patent.

As set forth in the patent, when the hawser has been paid out to normal length the drum of the master switch MS is thrown to its automatic position, deenergizing transfer relays 1TR and 2TR, with the result of deenergizing coils 1B', 2B' and BR' to stop the motor and set its brake.

Also as set forth in the patent, if then a surge occurs exerting an abnormal pull on the hawser, the tension switch drum TS will move to its position 1 to energize switch E, which is followed by energization of switches 1F, 2F and BR. Under these conditions the left hand terminal of coil E' of switch E has a connection through contacts 2TR³ of transfer switch 2TR, contacts 6, 6^b, 7^b, 7 to contact 21 of tension switch TS and

through contacts 21^a, 20^a and 20 to line L'. Coil E' when energized engages contacts E² to connect brake relay coil BR' in circuit and contacts E² complete a circuit from the supply of coil E' to and through contacts 1TR⁵ to 1F' and 2F'. 1F' and 2F' then respond to complete the circuit of the generator field winding F' for current flow in a direction to cause the motor to oppose payout of the line, the motor brake being at such time released. Also at this time switches 2D to 5D are energized to exclude resistors R² to R⁵ from the loop of the motor and generator armatures, resistor R' remaining in circuit to absorb the regenerative energy. If the surge increases sufficiently the tension switch TS progressively disengages contacts 22-22^a, 23-23^a, 24-24^a, 25-25^a to deenergize switches 2D to 5D for re-inclusion of the resistors controlled thereby, this permitting a higher payout speed with a limited increase in the retarding torque. As the surge decreases tension switch TS will reclose progressively the switches 5D, 4D, 3D and 2D, thereby keeping the retarding torque and subsequently the reclaiming torque at the desired value.

Also as stated in the patent, when the motor begins to reclaim the payed out hawser the friction switch 36 closes to complete the circuit of coil HR' which then closes contacts HR to short-circuit the holdout coil 1E² of the resistance switch 1D. After lapse of a time element switch 1D responds to exclude all resistance, whereby the full generator output is available for reclaiming.

As will now be apparent, where the aforementioned unusual conditions are met with and the drop in hawser pull is insufficient to permit the motor to rotate in reclaiming direction, the friction switch 36 will not function as just described and the added relay 1VR of the instant disclosure is provided to substitute temporarily for said friction switch 36.

The contacts of relay 1VR parallel the contacts of friction switch 36 and said relay contacts are normally engaged, said relay being designed and adjusted to disengage its contacts at all voltages other than that corresponding to a very slow speed of the motor. Accordingly the relay contacts are opened during payout until the motor approaches stalled condition, whereupon the relay contacts engage to shunt the open friction switch 36 and thereby initiate the cycle of control above recited as a function of closure of the friction switch. As the motor accelerates in reclaiming direction after closure of friction switch 36 relay 1VR opens, leaving the reclaiming cycle dependent upon said friction switch.

Thus need of any substantial drop in the hawser pull is unnecessary to initiate the reclaiming cycle and the voltage relay through the medium of which the difficulty is overcome in nowise interferes with the normal operation of the control inasmuch as it is energized to disengage its contacts except as the motor approaches stalled condition.

As aforesaid, the further description of control apparatus and its operation to be found in the aforementioned patent is equally applicable to the herein disclosed control minus the voltage relays 1VR and its connections.

What we claim as new and desire to secure by Letters Patent is:

1. For towing winch control, the combination with a motor to be operatively connected to the winch, means to energize said motor for motor torque opposing payout operation of the winch

and tending to effect reclaiming operation of the winch, and means to effect a reclaiming cycle of control for said motor following a payout cycle, the last mentioned means including for initiation 5 of the reclaiming cycle, means operatively associated with said motor to be set in an ineffective position by rotation of said motor above a very slow speed and to be caused to move to an effective position as said motor approaches zero speed in a payout cycle.

2. For towing winch control, the combination with a motor to be operatively connected to the winch, means to energize said motor for motor torque opposing payout operation of the winch and tending to effect reclaiming operation of the winch, and means to effect a reclaiming cycle of control for said motor following a payout cycle, the last mentioned means including for initiation of the reclaiming cycle, a relay having a control winding connected across the motor armature and being adjusted to assume an ineffective position as said motor accelerates above a very slow speed and to assume an effective position as said motor approaches zero speed on payout operation of the winch.

3. For towing winch control, the combination with a motor to be operatively connected to the winch, means to energize said motor for torque opposing payout operation of the winch and tending to effect reclaiming operation of the winch, and means to effect a reclaiming cycle of control for said motor following a payout cycle, the last mentioned means comprising for effecting such reclaiming cycle, means responsive to a slight 35 motion of the motor in reclaiming direction, and also comprising supplemental means for initiating the reclaiming cycle, which supplemental means is responsive to change in speed of said motor and becomes effective as said motor approaches zero speed on payout operation of the winch.

4. For towing winch control, the combination with a motor to be operatively connected to the winch, means to energize said motor for torque 45 opposing payout operation of the winch and tending to effect reclaiming operation of the winch, and means to effect a reclaiming cycle of control for said motor following a payout cycle, the last mentioned means comprising a friction switch 50 operatively related to said motor and responsive to a slight motion of said motor in reclaiming direction thereby to effect a reclaiming cycle and also comprising means responsive to change in speed of said motor for paralleling said friction 55 switch as said motor approaches zero speed on payout operation of the winch and for interrupting the parallel connection controlled thereby when said motor operates in reclaiming direction.

5. For towing winch control, the combination with a motor to be operatively connected to the winch, means to energize said motor for torque opposing payout operation of the winch and tending to effect reclaiming operation of the winch, 65 and means to effect a reclaiming cycle of control for said motor following a payout cycle, the last mentioned means comprising a friction switch operatively related to said motor and responsive to a slight motion of said motor in reclaiming 70 direction thereby to effect a reclaiming cycle and also comprising a relay having contacts in parallel with said friction switch and a control winding connected across the armature of said motor.
